UNITED STATES PATENT OFFICE.

EDWARD H. NOACK, OF STOCKTON, CALIFORNIA, ASSIGNOR TO MONARCH FOUNDRY COMPANY, OF STOCKTON, CALIFORNIA, A CORPORATION.

CONVEYER CLEAT.

Application filed June 10, 1926. Serial No. 114,885.

- This invention relates to improvements in conveyer cleats of that type particularly used on chain drag conveyers for sawdust and refuse in saw mills and like places.
- 5 The object of the invention is to produce a sectional cleat for the purpose which can be easily and quickly assembled on the chain and there secured in position. A further object is to produce a cleat which, when so assembled on the chain, is so constructed that the sectional parts may be accurately and rigidly fastened together so as to be in effect a single unitary structure. This will insure long life to the cleat and render its operation 10 properly effective.
- A further object of the invention is to produce a simple and inexpensive device and yet one which will be exceedingly effective for the purpose for which it is designed.
- 15 These objects I accomplish by means of such structure and relative arrangement of parts as will fully appear by a perusal of the following specification and claims.
- In the drawings similar characters of reference indicate corresponding parts in the several views:
- 20 Fig. 1 is a top plan view of a section of the drag chain and cleats as they appear in operative assembled position in the drag trough.
- 25 Fig. 2 is a side elevation of the sectional parts of a single cleat showing them in position assumed as they are being assembled into the chain, the chain link being shown in section.
- 30 Fig. 3 is a top plan view of the bottom section of the cleat.
- 35 Fig. 4 is a longitudinal vertical section through a completely assembled cleat.
- 40 Referring now more particularly to the characters of reference on the drawings, the numeral 1 designates the drag chain link into which the sectional cleat is assembled.
- The cleat comprises two complementary 45 members consisting of a bottom section 2 and a top section 3. The bottom section 2 is provided with a transverse recess 4 in its under face to receive one side of the link 1. The opposite side of the section 2 is cut away 50 as at 5 in a plane surface to a point just short of the center line of the cleat where it raises slightly to form a shelf 6 at the center of the cleat, from which shelf is a curved portion 7 rising upwardly in a substantially 55 90 degree arc to the top surface of the cleat.
- The cut out portion 5 as well as the shelf 6 and the top proper of the cleat section 2 is full surfaced from edge to edge of the cleat section.
- In the face of the shelf 6 is a cut-out recess 60 8 and in the face of the surface of the cut away portion 5 adjacent the front face of the cleat is another cut out recess 9.
- The cleat section 3 is made as a complement to the section 2 to make the complete 65 cleat and has a cut away portion 10 to fit over the shelf 6; a lug 11 to fit the recess 8; a lug 12 to fit the recess 9; and a curved end 13 to fit the curved portion 7. Immediately adjacent the curved end 13 is a recess 14, adapted, when the sections are assembled, to be parallel with and in the same vertical plane as the recess 4 so that the curved end of the sections 3 may be rotated 70 into engagement with the link 1 and complete the cleat tied into the link. Both sides of the section 3 have full surfaces from edge to edge, so that when the sections are assembled the under surface lies flush with the 75 surface of the cut away portion 5 and the 80 lugs 11 and 12 fit snugly into the recesses 8 and 9 to definitely and positively fix the proper relative position of the two complementary sections and make a substantially 85 solid and unitary cleat when the parts are riveted together, as will now be explained. In adjacent outer ends of the sections 2 and 3 are alined rivet holes 15 and 16 respectively. When the parts are assembled a rivet 17 is 90 set through these holes and secures the parts 95 together as a unit.
- After the sections are riveted together the flat contacting surface between the two and the abutting shoulders formed between the upraised shelf 6 and the cut out portion 10 95 together with the spaced lugs 11 and 12 fitting closely into the recesses 8 and 9 positively prevent either transverse or longitudinal loose movement between the sections 2 and 3, and hence shifting of parts and consequent wear and inefficient operation is completely avoided.
- 100 From the foregoing description it will be readily seen that I have produced such a device as substantially fulfills the objects of 105 the invention as set forth herein.
- While this specification sets forth in detail the present and preferred construction of the device, still in practice such deviations from such detail may be resorted to as do not form 110

a departure from the spirit of the invention, as defined by the appended claims.

Having thus described my invention what I claim as new and useful and desire to secure by Letters Patent is:

1. A conveyer cleat comprising two complementary cleat sections one section having a flat under surface provided with a transverse groove intermediate its ends and a flat surfaced cut away portion in its upper side extending from one end to a point short of the groove, an upraised shelf at the inner end of the cut away portion and crossing the plane of the groove and curving in an arc to the top surface of the cleat; the other section having a flat surface to lay against the flat surface of the cut away portion of the first section, a cut out portion to seat over the shelf, a curved end to engage the curve of the shelf, the inner end of said second section being provided with a transverse groove arranged to lie parallel with and in the same vertical plane as the transverse groove in the first section when the two are assembled together; and means to fasten the sections rigidly together.

2. A conveyer cleat comprising two complementary cleat sections, one having a flat under surface provided with a transverse groove intermediate its ends and having a flat surfaced cut away portion in its upper side terminating short of the transverse center line of the cleat section, an upraised shelf at the inner end of the cut away portion and crossing the center line of the cleat section and curving in an arc to the top surface of the cleat; the cut away portion and the shelf each having a recess in its surface; the other section having a flat surface to lay against the flat surface of the cut away portion of the first section, a cut out portion to fit over said shelf, a curved end to engage the curve of the shelf, lugs to fit into said recesses, the inner end of such second section being provided with a transverse groove arranged to lie parallel with and in the same vertical plane as the groove in the first section when the two are assembled together; and means to fasten the two sections rigidly together.

In testimony whereof I affix my signature.
EDWARD H. NOACK.
